(57) **CLAIM**

The ornamental design for a fencing tool, as shown and described.

DESCRIPTION

FIG. 1 is a front perspective view of a fencing tool showing my new design;

FIG. 2 is front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded front perspective view thereof;

FIG. 9 is an exploded front view thereof;

FIG. 10 is an exploded rear view thereof;

FIG. 11 is an exploded left side view thereof;

FIG. 12 is an exploded right side view thereof;

FIG. 13 is an exploded top view thereof; and,

FIG. 14 is an exploded bottom view thereof.

The greyscale shading shown in FIGS. 1-14 is provided solely for the purpose of showing surface contours. The dash-dot lines in FIGS. 1-14 and the areas within the dash-dot lines shown in phantom show portions of the fencing tool that form no part of the claimed design.
